GRAPPLE

Raleigh J. Williams, New Orleans, La.

Application December 30, 1943, Serial No. 516,298

2 Claims. (Cl. 294—106)

This invention relates generally to the class of grappling devices and pertains particularly to an improved hook or grapple designed for the handling of commodities loaded in cotton, burlap or sisal sacks.

A principal object of the present invention is to provide a grapple which can be employed for handling loaded sacks of the character stated, without injuring the sack or making an opening therein which would permit any of the contents to leak out. Such object is accomplished primarily by the provision of a plurality of coacting small pointed pins carried by relatively movable opposing bars in such a manner that the pins are capable of hooking into the filled sacks at opposite sides thereof and in the top belly in such a manner as to readily lift the sack without damaging it, from a stack of other filled sacks or lower the sack onto a pile and readily release the same.

Another object of the invention is to provide a grapple for the purpose set forth which is simple in construction and may be inexpensively manufactured.

Still another object of the invention is to provide a grapple of the character stated in which the bag penetrating pins are mounted in a supporting body in a novel manner whereby they may be readily replaced when and if necessary and in a manner to avoid damaging the bag material in which the pin points enter.

The invention will be best understood from a consideration of the following detailed description taken in connection with the accompanying drawings with the understanding that minor changes may be made in the structure so long as such changes do not depart from the invention as claimed.

In the drawings:

Figure 1 is a view in side elevation of the grapple of the present invention.

Figure 2 is a view in top plan of the same.

Figure 3 is a view in side elevation of the grapple, the lifting chains being omitted.

Figure 4 is a fragmentary view on an enlarged scale of a jaw bar.

Figure 5 is a section on the line 5—5 of Figure 4.

Figure 6 is a view of the top part of a grapple, a portion being in section, showing a modified lift means connected with the upper ends of the arms.

Referring now more particularly to the drawings it will be seen that the improved grapple comprises two pairs of relatively long arms, each

of which arms is designated 10. The arms are in crossed relation adjacent their upper ends and are pivotally coupled together by the nut and bolt pivot coupling 11. The major length of each of the arms is below the pivot member 11 for the pair and one pair of arms is disposed in spaced side by side relation with the arms of the other pair.

Above the pivot couplings 11 the ends of the 10 arms of one pair are joined to the ends of the arms of the opposite pair by the transverse bars 12 and at the point of connection of each arm with a bar 12 there is secured an end of a short chain section 13 and these short chain sections are 15 coupled together to a center ring 14 which is at the vertical center of the grapple.

At the outer ends of the lower longer portions of the arms 10 each arm is turned slightly downwardly away from the top of the grapple to form 20 approximately a 45° angle with the arm of which it forms a part, as indicated at 15.

The turned ends 15 of the arms of one pair are 25 permanently secured as by welding or in any other suitable manner, to a jaw bar 16 which is of a length materially greater than the width of the grapple so that a portion of such bar extends at each end outwardly beyond the plane of the arm to which it is attached.

Each of the jaw bars has formed transversely 30 therethrough a series of apertures 17 each of which is enlarged slightly at its inner end as indicated at 17' and extending through each aperture is the threaded shank portion 18 of a pin 19. The outer end of each pin shank 18 has a head 20 35 which engages the outer side or back of the jaw bar through which it extends and there is threaded upon the pin shank from the inner or pointed end, a nut 21 which is set back into the enlarged inner end portion 17' of the aperture 40 17 so that only the point of the pin is exposed for engagement with the body of a filled sack. With this construction it will be readily seen that the pins can be easily and quickly removed if necessary and at the same time the means by 45 which they are secured in position, namely the nut 21, is covered so that it cannot form a hole in the body of a sack which might permit some of the contents of the sack to leak out.

The points of the pins of one jaw bar are, of course, directed inwardly toward the points of the pins of the opposite bar and the extent to which the jaws of the grapple may be separated or opened depends upon the length of the short chains 13. It will be readily seen, however, that with a grapple constructed in accordance with

the present invention a filled sack of material may be readily grasped in the top belly between the pins of the opposing jaws so that the sack can be raised and lowered as desired and at the same time the pins because of the guarded manner in which they are secured in the jaws and because of the fact that they are relatively small, will not tear the sack material or form a hole in the same of sufficient size to allow any of the contents to be lost.

The grapple of the present invention is designed particularly to be used with a hoist of a suitable character to facilitate the loading or unloading of various vehicles such as trucks or cars and the like.

If desired the short chain section may be replaced by or there may be used instead of such chain section, the links 22 which as shown in Figure 6, has connected to its center a common ring 23.

I claim:

1. A grapple designed for the handling of filled sacks comprising pivotally coupled arms, jaw bars supported in spaced parallel relation by said arms for relative movement, a plurality of pin members extending through each of said jaw bars and each having a pointed end, the pointed ends of the pin

members of one jaw bar being opposed to those of the other jaw bar, said pins having heads upon their other ends engaging the jaw bars, and a nut threaded on each pin and counter-sunk in the adjacent jaw bar adjacent the pointed end of the pins.

2. A grapple for handling filled sacks comprising two pairs of crossed arms, the arms of each pair being pivotally joined, bars connecting the

10 upper ends of the arms of one pair with the upper ends of the arms of the adjacent pair to maintain the two pairs of arms in position for oscillation on a common axis, each of said arms at its other end being turned downwardly away from the said bars, a jaw bar connecting the turned end of

15 each arm of one pair with the corresponding adjacent end of the opposite arm of the other pair, said jaw bars extending at their ends beyond the outer sides of the pivoted arms, a plurality of pointed pin members carried by each jaw bar and directed in opposed relation with the pointed ends of the pin members of the other jaw bar, and connecting means between the four upper ends of the two pairs of arms by which the handling of the grapple is effected.

RALEIGH J. WILLIAMS.
